United States Patent Office.

T. W. PORTER AND H. K. PORTER, OF BOSTON, MASSACHUSETTS, ASSIGNORS
TO THEMSELVES AND CHARLES L. MARSTON.

Letters Patent No. 75,973, dated March 24, 1868.

IMPROVEMENT IN CARRIAGES.

The Schedule referred to in these Letters Patent and making part of the same.

TO ALL WHOM IT MAY CONCERN:

Be it known that we, T. W. PORTER and H. K. PORTER, of Boston, in the county of Suffolk, and State of Massachusetts, have invented a new and useful Improvement in Carriages; and we do hereby declare that the following is a full, clear, and exact description of the construction and operation of the same, reference being had to the accompanying drawings, making a part of this specification, in which—

Figure 1 is a perspective view of a side-spring shackle.

Figure 2 is a longitudinal vertical section of the same.

Figure 3 is a perspective view of a metallic hanging-bar end.

Figure 4 is a longitudinal vertical section of the same.

Figure 5 is a perspective view of a metallic hanging-iron socket.

Figure 6 is a transverse section of the same, taken in the axis of the hanging iron.

Figure 7 is a perspective view of a metallic hanging bar.

Figure 8 is a longitudinal section of the same.

Figure 9 is a top view of an axle-yoke and perch-stay.

Figure 10 is a perspective view of a metallic head-block.

Figure 11 is a vertical section, taken in the axis of the perch.

Figure 12 is a perspective view of a pole-crab; and

Figure 13 is a horizontal section of the same.

Similar letters indicate corresponding parts in the several figures of the same device.

The nature of our improvements consists in an improved spring-shackle, consisting of a three-sided link, and a bed-plate with a solid eye, and formed to receive an inverted axle-clip; the link and bed-plate being united by a wrought-iron bolt or rivet; in an improved hanging-bar end, so constructed as to receive the eye of the hanging iron in a cup or socket; in a hanging-iron cup, formed to embrace and secure the wood of the hanging bar, yet allowing the usual wood finish on the bar-end; in a hollow metallic hanging bar; in axle-yokes of malleable iron, combined with perch-stays of wrought iron; in hollow metallic head-blocks, with the perch-couplings, formed upon the head-block; and in a pole-crab, formed with the lateral arms hollow, as also hollow pole-strap studs.

All the foregoing parts being formed of malleable iron, in order to give them their peculiar construction, and at much less cost than if formed of wrought iron in the usual manner.

In figs. 1 and 2, A represents the bed-plate, which is formed with a solid eye, through which passes the rivet *a*; two holes *b b* for the ends of the clip, and a stud, *e*, which serves to prevent lateral motion of the plate upon the bed. The link *B* is formed three-sided, or with two flat sides, *d d*, united at one end by the bar *e*, upon which bar the eyes of the spring are closed; at one end of the sides *d d* are eyes for the rivet *a*. By thus forming the link three-sided, and combining it with the bed-plate by a rivet, the eyes of both are cast solid, instead of one being cast open in the usual clumsy manner. The bar *e* is of a smaller diameter than the ends of sides *d d*, so that the projecting edge of the sides curtains the eyes in the spring-ends. By forming the bed-plate like a clip-yoke, holes through either the bed or axle are avoided, thus leaving full strength, at less cost than in the common method.

In figs. 3 and 4, A represents the end of the hanging bar, upon which is fitted a metallic cap or end, *B*, which encloses the end of the bar in a socket, while straps extend a short distance upon the upper and under sides of the bar, and an end finish terminates the outer end of the socket. Where the hanging iron rests is a circular rim, *a*, surrounding the hole *b*, in which the hanging-iron bolt is inserted. The cavity or cup thus formed serves to receive the eye of the hanging bar, as is plainly shown in fig. 6.

In figs. 5 and 6, A represents the hanging-bar, and *B* a metallic socket or saddle, which is formed to sit astride of and prevent the splitting of the bar, as is shown, the two projections *c c*, enclosing and bearing against the sides of the bar, while two small perforated ears, *e e*, bear upon the top of the bar, and are the means of attaching the saddle thereto. *d* is a circular rim cast upon the saddle, and in the cup thus formed by

the rim the downward-projecting eye, formed upon the hanging iron *a*, is inserted, resting upon a disk, of leather *f*, while a screw-bolt, *b*, passing through the eye of the hanging iron *a*, the bottom of the saddle *B*, and the hanging bar *A*, serves to hold the hanging iron in place; the rim, *d*, serving to prevent all horizontal strain upon the bolt, or danger of rending the bar apart.

In figs. 7 and 8, *A* represents a metallic hanging bar, formed hollow beneath, but presenting a continuous surface at the sides and top. Around the bolt-holes *b b* are formed circular rims *a a*, thus forming a cup, which receives the eye of the hanging iron, as shown in fig. 6, for the purpose of relieving the hanging-bar bolt, which passes through holes *b b*, from lateral strain. *c c* are partitions, which unite the shell of the bar, and through the two central partitions the bolts *d d* pass, which secure the bar to spring *e*, as shown. A bar thus formed can be graceful in appearance and but slightly heavier than of wood.

In fig. 9, *A* represents a malleable-iron axle-clip yoke, formed with the usual axle-step *a*, and the clip-holes *b b*, while a short socket *c* extends at one end, in which is inserted the wrought-iron perch-stay *d*. This stay may be connected with the yoke by a male and female-screw thread, or it may be laid in the mould, and the malleable iron cast upon it.

In figs. 10 and 11, *A* represents a metallic head-block, which is formed hollow in the same manner as the metallic hanging bar, shown in figs. 7 and 8, that is, it has a continuous surface at the sides and on the top, except at the spring-seat, there being a cavity, *b*, extending between the bolt-holes *f f* of the fifth-wheel. Through the centre partition is the king-bolt hole *d*, and on either side of the centre are thin cross-bars, through which pass the spring-bolts in holes *e e*. *a* is the perch-coupling, which is formed upon and is part of the head-block. *B* is the perch, and *c* is a wrought-iron plate, secured to the under side of the perch, and through which the king-bolt passes. Either one or two of the perch-couplings may be formed upon the head-block, as the style of carriage may require, and while the strength of the head-block is greatly increased, the size and cost are greatly decreased.

In figs. 12 and 13, *A* represents the pole-crab, and *B* the end of the pole. The arms, *a a*, of the crab are formed hollow, as is plainly shown in fig. 13, the holes *c c* passing entirely through the arms, and the pole-strap studs *b b* are also formed hollow in the same manner; the poles *d d* extending through the studs.

By thus forming the arms *a a* hollow, they are stronger than solid arms of the same weight; besides, as malleable iron is strongest next the surface, the arms have an increased surface of the tougher metal; and by forming the studs *b b* hollow, they are larger of the same weight, and consequently cause less strain and wear upon the straps than smaller ones would.

Having thus described our invention, what we claim as new, and desire to secure by Letters Patent, is—

1. A spring-shackle, formed with the bed-plate *A* and the three-sided link *B*, united by the wrought-iron rivet *a*, substantially as described, and shown in figs. 1 and 2.
2. The stud *c* or its equivalent, formed upon the bed-plate, substantially as described, and shown in fig. 2.
3. The sides *d d* of link *B*, formed to extend beyond the bar *e*, and cover the spring-eye, substantially as and for the purposes specified.
4. The rim *a*, formed upon bar-end *B*, for the reception of the hanging iron, substantially as described, and shown in figs. 3 and 4.
5. The socket *B*, formed to receive the hanging iron *a*, and the bar *A*, figs. 5 and 6, substantially as and for the purposes specified.
6. The hollow metallic hanging bar *A*, substantially as described, and shown in figs. 7 and 8.
7. The rims *a a*, formed upon the metallic hanging bar *A*, substantially as described, and shown in figs. 7 and 8.
8. Combining the malleable-iron yoke *A* with the wrought-iron stay *d*, substantially as described, and shown in fig. 9.
9. The hollow metallic head-block *A*, substantially as described, and shown in figs. 10 and 11.
10. The perch-couplings *a*, formed upon the head-block *A*, substantially as described, and shown in figs. 10 and 11.
11. Forming the arms *a a* of the pole-crab hollow, substantially as described, and shown in fig. 13.
12. Forming the pole-strap studs *b b* hollow, substantially as described, and shown in figs. 12 and 13.
